UNITED STATES PATENT OFFICE

149,024

DESIGN FOR A NEGLIGEE OR SIMILAR ARTICLE

Alexander Roth, New York, N. Y., assignor to
Wirth-Gold Underwear Co., Inc., New York,
N. Y., a corporation of New York

Application July 3, 1947, Serial No. 140,098

Term of patent 3½ years

(Cl. D3—26)

To all whom it may concern:

Be it known that I, Alexander Roth, a citizen of the United States, residing in New York, in the county of Bronx and State of New York, have invented a new, original, and ornamental Design for a Negligee or Similar Article, of which the following is a specification, reference being had to the accompanying drawing, forming a part thereof, wherein:

Fig. 1 is a front perspective view of a negligee or similar article showing my new design.

Fig. 2 is a rear perspective view thereof.

I claim:

The ornamental design for a negligee or similar article, substantially as shown.

ALEXANDER ROTH.
